TIE LOADING MACHINE

Filed April 8, 1922

2 Sheets-Sheet 2

By Watson B. Coleman
Attorney

UNITED STATES PATENT OFFICE.

DANIEL H. MAHONEY, OF NORTH BEND, OHIO.

TIE-LOADING MACHINE.

Application filed April 8, 1922. Serial No. 550,851.

To all whom it may concern:

Be it known that I, DANIEL H. MAHONEY, a citizen of the United States, residing at North Bend, in the county of Hamilton and

5 State of Ohio, have invented certain new and useful Improvements in Tie-Loading Machines, of which the following is a specification, reference being had to the accompanying drawings.

10 This invention relates to loading machines, and particularly to means for loading ties, especially creosoted ties, into box cars or gondola cars.

In loading creosoted or otherwise treated ties into box cars, the creosoted ties while still very hot from the creosoting operation are run out of the plant on tram-cars and run into position adjacent the railway car and are then loaded onto the rail-

20 road car by hand. Inasmuch as the ties at all times are slippery and difficult to handle, and inasmuch as oftentimes the ties are very hot, there is a great difficulty in handling the ties and but slow work is made of the operation.

25 Furthermore, the ties have to be lifted from the tramcar onto a skid, shifted along the skid into the box car, and then slid on skids and trestles into place, and after a few tiers of ties have been built up, the ties have to be lifted into place. As a consequence of this, it is ordinarily difficult to lift the ties to a greater height than three feet and as a consequence the car is not properly filled with ties or properly loaded

35 with the maximum amount of ties which can be ordinarily accommodated.

With these facts in mind, the general object of my invention is to provide a loading machine so constructed that with a minimum of manual labor the ties may be lifted from the tramcar, discharged onto a chute, and slid into the door of the box car or gondola car and shifted into place in tiers within the car.

45 Ordinarily these ties are much longer than the width of the door of the box car, and a further object of the invention, therefore, is to provide means whereby these relatively long ties may be automatically guided in through the door of the box car and disposed in place therein.

A further object is to provide a machine of this character which, by a simple adjustment, may load first one end of the car and then load the other end of the car.

55 Another object is to provide a machine

of this character which, after one car has been loaded, may be shifted into position in front of the door of the next adjacent car and this car loaded.

60

Still another object is to provide a machine of this character which includes tie-engaging hooks, and provide means whereby the carriage supporting these hooks may be shifted in such position that any tie on the tramcar may be engaged by the hooks and hoisted.

65

A still further object is to provide a machine of this character so constructed that no tie releasing devices have to be provided, but in which the tie is released upon a downward movement of the tie carrier after it has been elevated to a proper position.

70

Other objects will appear in the course of the following description.

75

My invention is illustrated in the accompanying drawings, wherein:

80

Figure 1 is an end view of my improved loader showing the tie carrier in its initial position;

85

Figure 2 is a vertical sectional view showing the tie carrier moving upward and in a position just before it discharges the tie;

90

Figure 3 is a fragmentary view of the upper portion of the loader showing the tie carrier moving downward and the tie discharged;

95

Figure 4 is a top plan view of the construction illustrated in Figure 1 and showing in section the side wall of a car;

100

Figure 5 is a front elevation of the loader and a portion of a box car.

105

Referring to these drawings, it will be seen that my device comprises a supporting frame more or less rectangular in form and constructed of ordinary material, which supporting frame embodies the longitudinally extending sills 10 and the transverse braces 11. These sills and braces may be of angle iron, flat iron or any other suitable form. Preferably this frame 10 is mounted upon wheels 12 whereby the frame may be shifted from place to place.

110

Bolted to the forward portion of the frame 10 and extending vertically upward therefrom are the standards 13 which may be of angle iron, channel iron or have any other suitable or desired form, these standards being connected at their upper ends by a cross piece 14. Extending upward from the outer sill 10 and intersecting the standards 13 are the upwardly and forwardly

extending standards 15 which are illustrated as intersecting the standards 10 at the point 16 and being bolted thereto at this point and being braced from the standards 5 13 by the horizontally disposed braces 17.

Mounted upon the supporting frame so formed is a chute consisting of a downwardly and forwardly inclined plate 18 which is supported by a frame 19, the sides 10 of this frame extending upward and rearward, as at 20, and being rigidly bolted riveted or otherwise connected to the standards 13 and 15. This plate has upwardly extending end walls 21 and the upper margin 15 of the plate is formed with a pair of slots 22 extending transversely of the length of the plate. Inward of each slot is a finger or guide 23 which extends upward from the plate and then is downwardly and slightly forwardly extended, as 20 at 24. These guides 23 may be bolted, riveted or otherwise attached to the plate. One of the end walls 21 is abutted against the jamb of the door, as shown in Figure 25 4.

Extending downward and rearward from the rear ends of the frame 18 are the rails 25 which are illustrated as circular in cross section and illustrated as bolted to the ends 30 of the frame 18. This frame is further braced by braces 26 which are bolted or riveted to the frame 18 at the junction of the rails 25 and these braces extending upward and being bolted or riveted to the standard 13. The rails 25 at their upper ends are pivoted to the frame 18 and are shiftable outward or inward by means of braces 27. These braces 27 slide in guides 28 upon the standards 15 and the inner ends 40 of the braces are formed with a plurality of perforations 29, there being bolts 30 adapted to pass through any of these perforations 29 and through the standards 13 to support the braces 27 in their adjusted positions. The outer ends of the braces 27 45 are so formed as to bear against and support the rails 25.

It will be obvious that when the braces 50 27 are forced outward, the lower ends of the rails 25 will be spread outward away from the standards 15, and when the braces 27 are adjusted inward, the rails will be spaced a less distance from the standards 15. These rails are preferably connected 55 at the point of intersections of the braces 27 by a cross brace 31. These rails do not reach the ground but are always disposed in spaced relation thereto and are spaced apart a distance greater than the length of the frame A from which the ties are to be taken for loading.

Mounted to operate upon the rails is a tie lifting carriage consisting of a transverse bar 32 which may be made of wood, 60 metal or any other suitable material and

which is illustrated as having a wear plate 33 upon its inner face. This wear plate is so formed adjacent its ends as to engage the tracks, and I have illustrated for this purpose this wear plate 33 as being formed with depressed portions at its ends partially embracing the tracks 25. Pivoted to the bar 32 is a transverse rod 34. This rod is swingingly supported in suitable bearings 35 carried by the beam 32, and the extremities of the rod are angularly bent and normally depend in a vertical position and these angularly bent portions are bent forward and upward so as to provide hooks 36. The middle of the rod 34 is formed to provide a handle 37 extending in an opposite direction from the hooks. 70

Attached to the bar 32 is a bail 38, and a cable, either a wire rope, chain or like flexible member is attached to this bail 38 and extends upward and over a pulley 39 mounted on the bracket attached to the cross piece 14 and from this pulley the flexible member 39 extends to a second pulley 40 and then downward and over a winding drum 41 mounted upon the supporting frame 10. This drum may be driven by any suitable engine or power. Preferably an electric motor is mounted upon the frame which drives the drum. This hoisting drum is of any usual or suitable form commonly used in hoisting engines and forms no part of my invention. The hoisting drum is provided with the usual controlling levers, such as a clutch lever and a brake lever, 95 so that the hoisting drum may be clutched to the driving shaft of the drum or released therefrom and allowed to run free, the movement of the hoisting drum being 100 controlled by a brake.

Coacting with the chute and the downwardly extending plate 18 is a second chute 42. One end of this chute has its side walls 43 formed with an arcuate slot 44 terminating in an opening 45 whereby this end of the chute may be hung upon a stud bolt 46 projecting from a longitudinal member of the frame 18. A like stud 46 projects from the opposite end of the frame, and the side 115 wall of the chute at two different points are provided with the hook-shaped slot 44. The chute is longer than the width of the car door opening, and while one end of the chute 42, as illustrated, abuts against the wall b of the car B, the other end of the chute extends into the car behind the front wall of the car. Thus the chute 42 is not disposed parallel to the forward edge of the plate 18 but is at an angle thereto or laterally spaced therefrom. This end of the chute 42 is preferably supported by means of a clamp 47 which engages the jamb of the doorway. 120

It will be understood, of course, that the chute 42 is inclined downward and it will be 130

noted that the jamb of the doorway extends across the forward corner of the chute or plate 18. Thus when a tie moves downward on the plate 18, one end of the tie will 5 be engaged by the jamb of the car door, while the other end of the tie will move on downward and will slip into the chute 42 and then the tie will move down the chute 42 as a whole. Thus the chute 42 acts to 10 guide the tie into the car door and prevent the tie from becoming jammed. This is rendered necessary by the fact that, as before stated, the tie is longer than the width of the car door opening.

15 Preferably, and in order to prevent any possibility of the tie jamming against the jamb of the door against that end wall 21 which abuts the jamb and getting stuck, I provide a guide strip 48 which extends out 20 through a slot in the plate 18 and extends downward over the wall of the chute 42 so that the rear end of the tie will be retarded thus allowing the forward end of the tie to slip downward into the chute 42 and thus the 25 tie be guided longitudinally into the car, with no chance of this end of the tie striking against and possibly catching on the jamb of the door. Furthermore, this strip 48 acts to elevate this end of the tie so that 30 it will have a greater initial impetus down the chute 42.

In the operation of this invention, this machine is disposed opposite the car door and the chute 42 is adjusted to load one end of 35 the car. The tram or truck with the ties is moved into position in front of the loader and the rails 25 are shifted so that the carriage will move down into proper relation to the first ties to be hoisted, with the hooks 40 in a horizontal position. With the parts as shown in Figure 1, the operator then by means of the usual "pick" pulls the tie into position onto the hooks 36. The man controlling the hoisting drum then causes the 45 drum 41 to revolve and this through the strain applied to the cable 29 lifts the carriage up the tracks with the tie. Eventually the carriage reaches the inclined braces 26 and as the carriage moves up these inclined 50 braces 26, which form to this extent a continuation of the rails 25, the tie strikes the guide fingers 23 and is swung rearwardly so as to pass the upper end of the chute 18. If 55 now the cable be paid out by the drum, the carriage will move downward, the hooks will move through the slots 22 of chute 18, and the tie will be lifted upon the upper face of the chute and will slide down this chute 18. One end of the tie will strike the door jamb, 60 as before remarked, or strike the strip 48, and the other end of the tie will slide freely down and into the chute 42 and as a consequence the tie will be slightly diagonal to the plane of the car door so that one end will 65 enter the car door and move laterally before

the other end enters the car door, these car doors being approximately from 5 to 5½' wide and the ties being from 8 to 8½' long. While the tie is being shot down the chute 18 into the chute 42, the carrier is returning 70 to its original position ready to receive another tie, and as soon as it has reached a position convenient to receive this tie, the paying-out motion of the drum is stopped and the carrier held in this position. Then the 75 operator shifts another tie onto the hooks 36 and the operation is repeated.

If it be desired to bring the carrier more 80 nearly in alignment with the outside edge of the tramcar, it is an easy matter to adjust the braces 27 and shift these tracks 25 outward, or as the ties are removed from the tramcar these tracks may be shifted inward, the tracks always being spaced apart a greater distance than the tramcar so that this 85 motion of the tracks is permitted. Thus the carrier is brought into the exact position desired to make the handling of the ties most effective and to permit it to be done with the least possible amount of labor. After one-half 90 the car has been loaded, the chute 42 is turned from, say the position shown in Figure 4 where it is inclined downward and toward the left and has its opposite or left hand end lowered and connected to the car 95 door while the left hand end is connected to the corresponding stud 46 and the other half of the car is loaded. When the car has been completely loaded the chute 42 is removed and may be rested upon the chute 18 and 100 then the machine is moved along to the next succeeding car which is, of course, loaded in the same manner.

Inasmuch as the ties generally have to be 105 actually handled, pushed or shoved into position by manual exertion, a great deal of time is saved and the loading is materially expedited. As before remarked, it is extremely difficult to handle these ties, not only because of their slipperiness, but because of the heat of the ties, which in many 110 cases prohibits their being manually handled at all. With this construction, the chute 42 is so mounted that the car may be loaded with five tiers of ties and thus loaded 115 to what is practically the capacity of the car for ties. Where the ties are loaded manually upon the car, only three tiers of ties can be so loaded at each end of the car.

It will be seen that my machine depends 120 very largely upon the principle of holding back one end of the tie while the other end is allowed to slip into the door opening and then causing the tie to chute longitudinally into the car at a height which will permit 125 the tie to land on the top of a four-tier pile. The expedition with which ties may be handled is largely due to the fact that there is no unlatching device for the tie but the tie is automatically released from the carriage 130

upon the lowering of the carriage below the level of the upper end of plate 18 so that the operator simply has to wind up on the winding drum to elevate the carriage 5 and then release the winding drum and let the carriage go back to its original position and does not have to bother with the tie, which is automatically released from the carriage.

10 Where ties are being loaded upon gondola or flat cars, it is not necessary to use the chute 42. In that case the ties may be slid directly from the chute 18 onto the car, but the chute 42 permits the ties to be slid into 15 the doorway of a box car and furthermore permits the ties to be slid longitudinally toward the ends of the car.

While I have shown a machine which embodies the general principle of my construction, yet it will be understood that many changes might be made in the details of construction and arrangement of parts without departing from the spirit of the invention as defined in the appended claims.

25 I claim:—

1. Means for loading ties into cars comprising a supporting frame, a laterally inclined chute carried by the frame, means for hoisting ties and discharging them onto the chute with the ties extending transversely to the inclination of the chute, and a second longitudinally inclined chute disposed with its axis at an acute angle to the discharge edge of the first named chute.

35 2. Means for loading ties into cars comprising a supporting frame, a laterally inclined chute carried by the frame, means for hoisting ties and discharging them onto the chute with the ties extending transversely to the inclination of the chute, a second longitudinally inclined chute disposed with its axis at an acute angle to the discharge edge of the first named chute, and means whereby that end of the tie adjacent the upper end 40 of the second named chute shall be retarded to cause the opposite end of the tie to swing downward into the car door opening.

45 3. Means for loading ties into box cars comprising a supporting frame, a laterally inclined chute carried by the frame, means for hoisting ties and discharging them onto the chute, a second longitudinally inclined chute disposed at an acute angle to the discharge edge of the first named chute, the upper end of the second named chute being disposed inward of the adjacent end of the first named chute to permit the jamb of the car door to extend vertically across this end 50 of the first named chute to thereby impede that end of the tie adjacent the upper end of the second named chute and permit the opposite end of the tie to swing downward into the car door opening.

60 4. Means for loading ties into box cars comprising a supporting frame, a laterally

inclined chute carried by the frame, means for hoisting ties and discharging them onto the chute, a second longitudinally inclined chute disposed at an acute angle to the discharge edge of the first named chute, the upper end of the second named chute being disposed inward of the adjacent end of the first named chute to permit the jamb of the car door to extend vertically across this end of the first named chute, and a guide strip extending from the first named chute adjacent the upper end of the second named chute and extending over the second named chute whereby to impede that end of the tie adjacent the upper end of the second named chute and permit the opposite end of the tie to swing downward into the car door opening.

65 5. Means for loading ties into box cars comprising a supporting frame, a laterally inclined chute carried by the frame, means for hoisting ties and discharging them onto the chute, a second longitudinally inclined chute disposed at an acute angle to the discharge edge of the first named chute, the upper end of the second named chute being disposed inward of the adjacent end of the first named chute to permit the jamb of the car door to extend vertically across this end of the first named chute, and a guide strip adjacent the upper end of the second named chute and extending over the second named chute, the end of the guide being upwardly extended whereby to impede that end of the tie adjacent the upper end of the second named chute and permit the opposite end of the tie to swing downward into the car door opening.

70 6. Means for loading ties into box cars comprising a supporting frame, a laterally inclined chute carried by the frame, means for hoisting ties and discharging them onto the chute with the ties at right angles to the inclination of the chute, a second longitudinally inclined chute disposed at an acute angle to the discharge edge of the first named chute, the upper end of the second named chute having means whereby it may be operatively engaged with the first named chute inward of the end thereof, and means on the opposite end of the second named chute whereby it may be clamped upon the jamb of the car door opening with this end 75 of the chute inward of said jamb.

75 7. Means for loading ties into box cars comprising a supporting frame, a laterally inclined chute carried by the frame, means for hoisting ties and discharging them onto the chute with the ties at right angles to the inclination of the chute, a second longitudinally inclined chute disposed at an acute angle to the discharge edge of the first named chute, the side wall of the upper end of the second named chute having an 80

arcuate slot, the first named chute having a bolt operatively projecting from it with which the slot is adapted to engage, the lower end of the second named chute having means whereby it may be clamped upon the jamb of a door opening, with the chute inside of the jamb.

8. Means for loading ties into cars comprising a supporting frame, a laterally inclined chute mounted thereon, spaced rails extending outward and downward from a point above the chute and spaced apart a distance greater than the length of the tie to be elevated, a tie carrier movable over said rails, power operated means for raising or lowering the carrier along the rails, and tie engaging means mounted upon the carrier.

9. Means for loading ties into cars comprising a supporting frame, a laterally inclined chute mounted thereon, spaced rails extending outward and downward from a point above the chute and spaced apart a distance greater than the length of the tie to be elevated, a tie carrier movable over said rails, power operated means for raising or lowering the carrier along the rails, and tie engaging hooks swingingly mounted upon the carrier.

10. Means for loading ties into cars comprising a supporting frame, a laterally inclined chute mounted thereon, spaced rails extending outward and downward from a point above the chute and spaced apart a distance greater than the length of the tie to be elevated, a tie carrier movable over said rails, power operated means for raising or lowering the carrier along the rails, and a pair of connected tie engaging hooks swingingly mounted upon the carrier and depending therefrom and having a handle common to both hooks.

11. Means for loading ties onto box cars comprising a supporting frame, a laterally inclined chute connected thereto, spaced rails extending outward and downward from a point above the upper end of the chute spaced apart a distance greater than the length of the tie to be loaded, a carrier extending over and movable on said rails, a power operated cable mounted upon the frame above the chute and connected to the carrier to raise and lower it, tie engaging hooks swingingly mounted upon the carrier, and guides mounted upon the upper end of the chute and adapted to engage the tie to swing the tie and hooks outward to permit the tie to pass the upper end of the chute, the upper end of the chute being formed with slots to permit the downward passage of the hooks as the carrier moves downward.

12. Means for loading ties comprising a vertically extending frame, a downwardly inclined chute mounted thereon, rails ex-

tending downward and outward from a point above the upper end of the chute, a carrier moving over said rails and having means for engaging the tie, and means permitting the carrier, tie and tie engaging means to pass upward to a point immediately above the upper end of the chute, said means upon a downward movement of the carrier retaining the tie upon the upper end of the chute but permitting the downward movement of the carrier and tie engaging means past the upper end of the chute.

13. A tie loading mechanism of the character described including a vertical supporting frame, a downwardly inclined chute mounted thereon, rails extending downward and outward from a point above the chute, a carrier movable over said rails, power operated means for raising or lowering the carrier upon the rails, and means adapted to automatically release the tie from the carrier and deposit it on the chute upon the downward movement of the carrier past the chute after it has been raised to a point above the upper end of the chute.

14. A tie loading mechanism of the character described including a supporting frame, a downwardly inclined chute mounted thereon, rails extending downward and outward from the supporting frame, braces mounted upon the supporting frame, extending rearward therefrom and supporting the rails, a carrier movable over said rails and having tie engaging means, and power operated means for raising or lowering the carrier, said braces being longitudinally adjustable to shift the rails outward or inward.

15. A tie loading mechanism of the character described including a supporting frame, a downwardly inclined chute carried thereby, rail sections pivotally connected to the upper end of the chute and extending outward and downward therefrom, means for supporting the rail sections in adjusted position, rail sections connected to the upper ends of the first named rail sections and extending upward and forward and connected to the supporting frame at a point forward of the upper edge of the chute, a tie carrier comprising a longitudinally extending bar resting upon said rails and movable therealong, a pair of tie engaging hooks swingingly mounted upon the bar and normally depending therefrom, a power operated cable operatively connected to the bar whereby it may be raised and lowered, guides attached to the upper margin of the chute and projecting rearward therefrom and downward whereby to shift the tie outward to permit it to pass the upper edge of the chute, said chute having inwardly extending slots to permit the downward passage of the hooks when the tie carrier is raised past the chute.

16. Means for holding ties into cars comprising a supporting frame having supporting wheels whereby the frame may be shifted longitudinally parallel to a line of cars, a downwardly inclined chute mounted upon the supporting frame, rails extending outward from the supporting frame above the said chute, means for supporting the rails with their outer ends above the ground and adjusting said rails toward or from the supporting frame to thereby permit the rails to extend over a tramcar and to be adjusted transversely of the tramcar, a

carrier extending across and resting upon both of said rails, freely swinging hooks mounted upon the carrier and adapted to engage a tie on the tramcar and lift it to the chute, power operated means for raising or lowering the carrier, and means adapted to automatically release the tie from the hooks and leave it on said chute when the tie carrier is lowered past the chute. 15

In testimony whereof I hereunto affix my signature.

DANIEL H. MAHONEY.
